TEST DEVICE FOR DETECTING VARIOUS CONSTITUENTS IN FLUIDS

Richard Gordon Rosenfield, South Bend, Ind., assignor to
Miles Laboratories, Inc., Elkhart, Ind., a corporation
of Indiana

Filed Apr. 1, 1969, Ser. No. 16,548

Term of patent 14 years

Int. Cl. D10—99

U.S. Cl. D16—2

FIGURE 1.

FIGURE 2.

FIGURE 3.

FIG. 1 is a front view of a test device for detecting various constituents in fluids which embodies my new design; and

FIG. 2 is an edge showing of the test device shown in FIG. 1.

FIG. 3 is a rear perspective view showing the test device of FIG. 1.

I claim:

The ornamental design for a test device for detecting various constituents in fluids, as shown and described.
